Primary Examiner — John R Yeh(74) *Attorney, Agent, or Firm* — Smart & Biggar LLP(57) **CLAIM**

We claim the ornamental design for a cleaning tool, as shown and described.

DESCRIPTION

FIG. 1 is a perspective view of our new design for a cleaning tool;

FIG. 2 is a top plan view thereof;

FIG. 3 is a bottom plan view thereof;

FIG. 4 is a front elevation view thereof, the rear being identical; and,

FIG. 5 is a side elevation view thereof, the other side being identical.

The broken lines in the figures represent portions of the cleaning tool that form no part of the claimed design.
